US0D1020735S

(12) **United States Design Patent** (10) Patent No.: **US D1,020,735 S**
(45) Date of Patent: ** Apr. 2, 2024

(54) **TABLET COMPUTER**

(71) Applicant: **MUSE Electronics GmbH**, Vienna (AT)

(72) Inventor: **Mag. Philipp Lechner**, Vienna (AT)

(73) Assignee: **MUSE ELECTRONICS GMBH**, Vienna (AT)

(**) Term: **15 Years**

(21) Appl. No.: **29/747,590**

(22) Filed: **Aug. 24, 2020**

Related U.S. Application Data

(62) Division of application No. 35/506,705, filed on Oct. 4, 2018 (U.S. filing date under 35 U.S.C. 384), and having an international filing date of Oct. 4, 2018, now Pat. No. Des. 895,612.
